Attorney

UNITED STATES PATENT OFFICE.

WILLIAM C. CARR, OF BUFFALO, NEW YORK, ASSIGNOR TO THE AUTOMATIC TRANSPORTATION COMPANY, OF BUFFALO, NEW YORK, A CORPORATION OF ARIZONA.

INDUSTRIAL TRUCK.

Application filed February 9, 1922. Serial No. 535,245.

To all whom it may concern:

Be it known that I, WILLIAM C. CARR, a citizen of the United States, residing at Buffalo, in the county of Erie and State 5 of New York, have invented certain new and useful Improvements in Industrial Trucks, of which the following is a specification.

This invention relates to improvements in 10 motor-driven industrial trucks of the type wherein a lifting platform is provided for picking up or depositing the loaded skid.

The invention relates particularly to improvements in the mechanism for operating 15 the lifting platform. The principal object is to provide mechanism which shall be durable, simple in structure and compact in organization, and which shall secure the highest degree of efficiency in the operations 20 of raising and lowering said platform, such efficiency having a three-fold aspect, namely speed of operation consistent with safe handling of the objects to be moved, economy of power, and extent of lift. A further object is to make simple and effective provision 25 for maintaining the platform stable in a horizontal plane, regardless of the weight of any loads upon its projecting end portions.

With the above objects in view the invention 30 consists generally in novel details of structure and organization of the operating gearing for the lifting platform and in the operative connections between said gearing 35 and said platform.

An embodiment of the invention is illustrated in the accompanying drawings, wherein:

Figure 1 is a partial side elevation of a 40 truck in which the features of improvement are incorporated, the platform being in its lower position.

Figure 2 is a partial elevation of the opposite side of the truck, the platform being 45 in its elevated position.

Figure 3 is a view, partly in side elevation and partly in longitudinal section, showing details of the worm gearing which is directly driven by the shaft of the operating motor.

Figure 4 is a cross section on the line 4—4 of Figure 3.

Figure 5 is a longitudinal section on the line 5—5 of Figure 4.

Figure 6 is a sectional view on the line 6—6 of Figure 1.

The features of improvement are applicable to a truck of the general type shown in my prior Patent, No. 1,248,075 of November 27, 1917, and which includes a frame 1 supported by front and rear wheels (whereof only the rear wheels 2 are shown), a propelling motor 3 connected by suitable gearing 4 to the rear wheels, a lifting platform 5, a motor 6 for the operation of said platform, 60 and storage batteries 7 as the source of current for the operation of the motors 3 and 6. The batteries 7 may be conveniently supported above the motors and their associated gear trains and the platform 5 is, of course, 65 arranged in front of the motors and above the frame 1. The platform 5 is directed rearward and upward or forward and downward by suitable means, preferably of the construction shown in my said prior patent 70 and consisting of raising blocks 8 secured to the under face of the platform and having inclined bearing edges 9 terminating at their lower ends in flat, horizontal bearing surfaces 10, said blocks co-operating 75 with rollers 11 having suitable fixed bearings in parts of the frame 1.

Where, as preferred, the movements of the platform 5 are directed by the co-operating blocks 8 and rollers 11, said platform is operatively connected to a transverse shaft 12, the connections including a crank arm 13 on said shaft and a suitable linkage between said crank arm and the platform. Preferably, however, and in accordance with certain 85 specific features of the invention, the connecting linkage is of the construction shown, that is to say it includes a link 14 pivoted to a bracket 15 at the front end of the platform and connected by another link 90 16 to the crank arm 13, and a radius arm 17 having a fixed pivot 18 on some part of the framing or other stationary part and also connected to the mutual pivot 19 of the links 14 and 16, the function of the arm 17 95 100

being to prevent the platform from tipping in consequence of a load on either end portion, i. e., portion projecting beyond the rollers 11.

- 5 According to the invention the motor 6 for the operation of the lifting platform has its axis at an angle to the axis of the crank arm 13, and its shaft drives the worm wheel 20, which is preferably coaxial with 10 said crank arm and is connected thereto by spur reduction gearing. The shaft 21 of the motor 6 is connected by a suitable coupling 22 to a coaxial shaft 23 which carries a worm 24 in mesh with the worm wheel 20, 15 the shaft 23 and worm wheel 20 being enclosed in a suitable casing 25 and having suitable anti-friction bearings. The worm wheel 20 is mounted upon a transverse shaft 26 which carries the initial element 27 of 20 the spur gear reduction train.

In the construction preferred the shaft 26 is also utilized as the support for the final element 28 of the reduction train, the hub of the gear 28 being extended to provide the 25 shaft 12 above mentioned and upon which the crank arm 13 is keyed. The reducing spur gear is completed by elements 29 and 30 mounted on a counter-shaft 31. The gear 27 is small and meshes with the gear 29 30 which is large and the gear 30 which is small meshes with the gear 28 which is large and thereby drives the shaft 12 from the shaft 31. The spur reduction gear comprising the elements described is enclosed in a suitable 35 casing 32.

The coupling 22 is preferably fashioned to provide a brake drum for co-operation with brake elements 35 which are movably mounted upon suitable supports and are 40 pressed into engagement with said drum by actuating springs 36. The brake elements 35 are disengaged from the drum by a cam 37 which works in opposition to the springs 36 and is mounted on a rock shaft 38 having an arm which is connected by a link 39 to the core of a solenoid 40. When the current is on for the operation of the motor 6 the solenoid is energized and through the 45 connections described moves the cam 37 to a position in which it holds the brake elements 35 disengaged. When the current is cut off the springs 36 effect the engagement of the elements 35 with the brake drum and the rotation of the motor is thereby arrested. 50 The means for starting and stopping the motor 6 form no part of the present invention and the following elements of such means are enumerated merely for the purpose of identification. The controlling 55 switch is enclosed in a casing 41 and is operated by a vertically movable rod 42 suitably connected to a controlling handle 43 at the rear of the truck. The connections between the handle 43 and the rod 42 include a 60 lever 44 having an extension portion 45 by

means of which the switch may be operated automatically in connection with the raising and lowering of the platform 5, the extension portion being directly engaged by the front end of the platform when the latter is raised and being engaged and operated by a hook connection 46 when the platform is lowered. As to these features a companion application Serial No. 535,246 has been filed.

70

75

The gearing for the operation of the platform 5 operates with more rapidity and with less resistance to the motor than the gearing shown in my said prior Patent No. 1,248,075 while at the same time effecting a lift of the 80 platform 5 through a greater vertical extent. Hence greater economy both in power consumption and in the time required for the use of the truck is effected while the increase of the vertical movement of the platform 5 85 will greatly facilitate the use of the truck under certain conditions more or less frequently encountered in industrial plants. The present gearing has the same advantage as the gearing shown in my patent referred 90 to, namely the platform 5 is raised by the movement of the crank 13 through half a revolution and is lowered during the movement of the crank through the remaining half revolution whereby it is unnecessary to 95 reverse the motor 6 in raising and lowering the platform. A further advantage of the gearing herein described and in accordance with the features of the invention is that the actual descent of the platform may be 100 accomplished under the weight of the load and does not require to be accomplished under power. Thus in effecting the lowering of the platform in order to deposit the loaded skid upon the floor the motor is operated to 105 move the platform horizontally forward sufficiently to disengage the bearing surfaces 10 from the rollers 11, after which the current may be cut off and the platform 5 may be permitted to descend under the weight 110 of the load, that is to say to "coast" to its lower position.

Having fully described my invention, I claim:

1. In an industrial truck, the combination of a lifting platform, an operating crank therefor, link connections between said platform and crank, a supporting frame, rollers and co-operating cam elements mounted on said frame and platform respectively, and constituting means for raising or lowering said platform in accordance with the direction of the movements effected by said link connections and a radius arm pivotally mounted at a fixed point and joined to said link connections to prevent the platform, as elevated, tilting in either direction in consequence of a load borne on either end thereof.

115

120

125

2. In an industrial truck, the combination 130

of a lifting platform, an operating crank therefor, link connections between said platform and crank, a hollow transverse shaft upon which the crank is mounted, an operating motor having its axis at an angle to said shaft, a worm wheel, a transverse shaft carrying the worm wheel and projecting into said hollow shaft, a shaft coaxial with and

driven by said motor and having a worm for engagement with said worm wheel and a spur gear reduction train interposed between the coaxial worm wheel-carrying and crank-carrying shafts.

In testimony whereof I affix my signature.

WILLIAM C. CARR.
